United States Patent Office.

QUIMBY S. BACKUS, OF WINCHENDON, MASSACHUSETTS.

Letters Patent No. 91,068, dated June 8, 1869.

IMPROVED VISE.

The Schedule referred to in these Letters Patent and making part of the same.

To all whom it may concern:

Be it known that I, QUIMBY S. BACKUS, of Winchendon, in the county of Worcester, and State of Massachusetts, have invented certain new and useful Improvements in Vises; and do hereby declare that the following is a full, clear, and exact description thereof, reference being had to the accompanying drawings and to the letters of reference marked thereon, making a part of this specification.

The nature of my invention consists in the construction of a vise, which can be secured to the table or bench in any desired position, and in the arrangement of the devices hereafter set forth and explained.

Figure 1 is a section-view of my invention.

Figure 2 is an end view of the stationary jaw.

Letter A represents the base of the vise, which rests upon the disk B, and from the end of which the stationary jaw C rises.

Formed, upon the top of the base is the cylinder D, upon which the movable jaw E moves back and forth.

In the bottom of this base there is an elongated slot cut, extending nearly its whole length, so that the whole vise can be moved to any desired position on the table, or can be entirely removed, at pleasure.

Passing through the stationary jaw is the screw-shaft F, by means of which the movable jaw is operated.

This shaft has a flange cut all the way around its neck, in which the stop G fits, so as to hold it in place.

Extending outward, from the inner side of the stationary jaw, is a tube, H, which may be either screwed in or cast with the jaw, and which serves to prevent filings, dirt, &c., from falling upon the screw-shaft.

Extending outward from the movable jaw E there is a similar tube, I, which is small enough to fit in the one from the jaw C, thus forming a complete case for the screw-shaft, from one end to the other.

Upon the back end of this tube, inside of the jaw, there is a screw-thread cut, in which the shaft F gears, so as to move the jaw back and forth.

In the bottom of this jaw there is an opening made, which fits snugly over the top of the cylinder D, (as

seen in fig. 2,) while its lower edges rest upon the top of the base, thus serving to hold it perfectly steady and firm in every respect.

Extending upward, through the top of the table, is a hollow screw-shaft, K, upon the top of which is the flat disk B, which forms a bed, upon which the vise rests.

Upon this shaft is placed the nut L, by means of which it is secured firmly to the table.

Passing up through the hollow screw-shaft K, there is a second, but smaller one, M, which serves to fasten the vise in any desired position.

Upon the top there is formed a head, N, which moves back and forth in the slot formed in the base, while upon the bottom there is a thumb-screw, O, by which the vise is secured in place.

Having thus fully described my invention,

What I claim, and desire to secure by Letters Patent, is—

1. The combination of the hollow screw-shaft K, with a disk, B, upon its top, screw-rod M, flanged head N, clamping-screw L, and screw O, with the grooved cylinder D, all substantially as and for the purposes specified.

2. The jaws E and C; screw-shaft F, tubes H and I, dog G, screw-rods K and M, disk B, nuts L, and thumb-screw O, when all are combined to form a vise, substantially in the manner and for the purpose specified.

3. In combination with the stationary jaw C, the cylinder D, with a rounded upper surface, and with an oblong slot in the bottom, leading into a semicircular recess, within which slides the head N, which is prevented from being disengaged by the shoulder formed near the outer end of said cylinder, substantially as set forth.

In testimony that I claim the foregoing, I have hereunto set my hand this 22d day of May, 1869.

Q. S. BACKUS.
